UNITED STATES PATENT OFFICE.

HERBERT T. HERR, OF PHILADELPHIA, PENNSYLVANIA, ASSIGNOR TO WESTINGHOUSE ELECTRIC AND MANUFACTURING COMPANY, A CORPORATION OF PENNSYLVANIA.

NOZZLE-CONTROL MECHANISM FOR STEAM TURBINES.

Application filed January 3, 1923. Serial No. 610,488.

To all whom it may concern:

Be it known that I, HERBERT T. HERR, a citizen of the United States, and a resident of Philadelphia, in the county of Philadelphia and State of Pennsylvania, have invented a new and useful Improvement in Nozzle-Control Mechanism for Steam Turbines, of which the following is a specification.

10 My invention relates to elastic-fluid turbines and it has for its object to provide improved means for cutting in and out nozzles whereby variations in load may be readily taken care of.

15 A further object of my invention is to provide a plurality of nozzle groups, under the control of suitable governor mechanism, so that the groups and the nozzle passages thereof are covered and uncovered one at 20 a time and in succession in order to take care of varying power demands.

Apparatus made in accordance with my invention is illustrated in the accompanying drawings forming a part of this application, in which Fig. 1 is a sectional view of a turbine showing my improved nozzle control apparatus applied thereto; Fig. 2 is a sectional view taken along the line II-II of Fig. 1; Fig. 3 is a fragmentary detail of 25 a portion of my improved nozzle control apparatus; and Fig. 4 is a sectional view taken along the line IV-IV of Figs. 1 and 2.

It is common practice, in connection with 30 turbines of the impulse type, to cut in or out nozzles to take care of varying power requirements. It is the object of my invention to provide apparatus of this character which is simple in construction, 35 highly responsive to changes in power requirements, and which is economical, both from the standpoint of manufacture and from that of operation. In accordance with my invention, I provide a primary group of nozzles which are at all 40 times open to the steam chest and secondary and tertiary groups of nozzles which are adapted to be opened and closed one at a time and in succession with respect to the 45 steam chest, the nozzle openings of the secondary and tertiary groups being opened and closed in succession, whereby variations in power requirements may be taken care of with a high degree of flexibility.

The apparatus for opening and closing 55 the nozzle openings of the secondary and tertiary groups is operated by a suitable governor. If the power developed by the normally open group of nozzles is insufficient, then the nozzles of the secondary group are successively opened in order to develop more power to meet the increased demand. Should the power developed, with the constantly open group of nozzles and with the group of secondary nozzles 60 entirely open, be insufficient, then the nozzles of the tertiary group are successively opened in order that more power may be developed.

Referring now to the drawings for a more detailed description of my invention, 70 I show a turbine casing 10 containing a rotor 11 provided with suitable energy abstracting elements including a first impulse stage, at 12. The turbine casing is provided with an interior nozzle box or steam chest 75 13 having a suitable steam inlet 14, a primary group or block of nozzles 15 constantly open to the blading of the stage 12, and secondary and tertiary groups or blocks of nozzles 16 and 17 which are 80 adapted to be opened successively in accordance with the power requirements. With the nozzle groups 16 and 17 closed, if the demand for power should increase, the nozzles of the secondary group are successively opened to meet the increased power 85 demand. Further demands for power may result in the opening of all the nozzles of the secondary group and then in the successive opening of the nozzles of the tertiary 90 group 17.

The secondary and tertiary group of nozzles 16 and 17 are provided with similar valve constructions in order to secure the opening and closure of the nozzle passages 95 in the manner just referred to. The valve constructions including flexible webs 20 attached at their upper ends to the nozzle box by any suitable means, for example, by the bolts 21, and the lower ends of the webs are secured to the lower ends of curved rockers 22. With this construction, if a rocker is moved in one direction, its cooperating web is wrapped about its curved surface with the result that the nozzle openings are exposed, whereas movement of the rocker in the other direction results in closure of the nozzle openings.

The rockers 22 of the secondary and tertiary groups of nozzles 16 and 17, respectively, are operated in a successive manner by means of governor mechanism shown at 23, operating preferably through a fluid relay at 24. The operating mechanism between the governor and the rockers 22 includes a leverage connection which assures the opening of the secondary group of nozzles first and then the opening of the tertiary group of nozzles.

The leverage connection consists of a link 25, which is operated from the governor, and which is pivotally connected, at 26, to a floating lever 27. One end of the floating lever 27 is pivotally connected, at 28, to a link 29, the lower end of the latter being pivotally connected, at 30, to the crank arm 31 of the rocker 22 of the secondary group. The other end of the lever 27 is pivotally connected, at 31, to a link 32, which is pivotally connected, at 33, to the crank arm 31 of the rocker 22 of the tertiary group of nozzles. The pivotal connection 26 is arranged nearer to the pivotal connection 28 than to the pivotal connection 31 in order to assure that, upon upward movement of the rod 25, the rocker 22 of the secondary nozzle group shall be moved first in order to expose the nozzle passages thereof, the lever 27, during this operation, fulcruming about the pivotal connection 31. An abutment 35 is arranged above the lever 27 so that when the rocker 22 of the secondary nozzle group 15 has been moved so as to expose all of the nozzle passages thereof, the lever 27 will then fulcrum about the abutment 35 with the result that, if further upward movement of the link or rod 25 takes place, the rocker 22 of the tertiary nozzle group 17 is moved upwardly in order to expose the nozzle passages thereof. Upon a decrease in power, the rocker 22 of the tertiary nozzle group 17 moves downwardly to close the tertiary nozzles; and, after the tertiary nozzles are closed, the rocker 22 of the secondary nozzle group 16 moves downwardly to close the nozzle passages thereof.

The specific valve construction of the secondary and primary nozzle groups 16 and 17, is essentially the same so that a detailed description of one will suffice. As may be seen from Figs. 2, 3 and 4, the nozzle passages are preferably covered by means of a seat member 37 which is provided with perforations 38 above the nozzle passages. The provision of perforations in this way reduces losses incident to wire-drawing and the reticulated construction constitutes a support for the flexible web 20, thereby preventing the bulging and sticking of the web in the nozzle opening.

The rockers 22 are provided with convex surfaces 39 about which the webs 20 are wrapped when the rockers are moved in one

direction. The webs 20 are secured to the lower ends of the rockers 22 by any suitable means, for example, the screws or bolts 40 so that, upon upward movement of the rockers, the webs are wrapped about the convex surfaces 39, with the result that the nozzle passages of the secondary and tertiary groups 16 and 17 are opened in the manner stated.

A chain construction is provided for each rocker member 22 in order to maintain the webs 20 taut and in firm engagement with the seats 37. Chains 41 are shown secured to the upper ends of the rockers 22, and they are provided with links 42 at their lower ends which pass through walls of the steam chest or nozzle box 13. Equalizing levers 43 have eyes which fit around the links 42 and nuts 44 are carried by the links below the levers 43 so that the chains 41 may be placed substantially in equal tension. The levers 43 possess sufficient inherent flexibility so that a satisfactory tensioning of the chains may be had.

As will appear from Figs. 2 and 4, the chains 41 are arranged to cooperate with seats 45, concentric with the convex surface 39, so that at least half of each chain projects above the convex surface 39 when in contact with its seat 45. Owing to the projection of the chains in this way, it is necessary to provide clearance therefor at the sides of the nozzle passages in order that a rocker member 22 and its web 20 may firmly engage a seat 37. Accordingly, therefore, the nozzle passages are, in part, provided in plate members 46 which are of sufficient thickness to provide the needed clearance for the chains. With this arrangement of chains, the webs 20 are maintained taut and the tension of the chains has an effective component tending to maintain the rocker and the webs in firm engagement with the seats 37.

From the structure described, operation of apparatus made in accordance with my invention will be apparent. If the turbine is loaded beyond the capacity of the primary nozzle group 15, the nozzle passages of the secondary nozzle group 16 are successively opened in response to the governor 23. With further increases in load, more and more of the nozzle passages of the secondary group are opened until, at last, all of such nozzle passages are open. If the load should increase still further, the floating lever 27 fulcrums about the abutment 35 and the rocker 22 of the tertiary nozzle group 17 is moved to expose nozzle passages thereof. A decrease in load results in closure of the tertiary nozzles first and then the closure of the secondary nozzles.

While I have shown my invention in but one form, it will be obvious to those skilled in the art that it is not so limited, but is

susceptible of various other changes and modifications, without departing from the spirit thereof, and I desire, therefore, that only such limitations shall be placed thereupon as are imposed by the prior art or as are specifically set forth in the appended claims.

What I claim is:

1. In a turbine, the combination of a nozzle block having a plurality of nozzle openings therein, a flexible member secured to one end of the block and adapted to cover and uncover the nozzle openings, a convexly-faced rocker member secured to the other end of the flexible member and adapted, when rocked, to cause the flexible member to be wrapped or unwrapped thereabout to uncover or cover said nozzle openings, and flexible members cooperating with said convexly-faced member laterally of said first flexible member to maintain the latter taut and in contact with the nozzle block. 55
2. In a turbine, the combination of a nozzle block having a plurality of openings therein, a flexible member secured to one end of the nozzle block for covering and uncovering the nozzle openings, a convexly-faced rocker member to which the other end of the flexible member is secured, flexible members disposed laterally of the first flexible member and secured to the convexly-faced member, and yieldable means cooperating with said laterally disposed flexible means, whereby the latter are placed in tension to maintain the first flexible member taut and in contact with the nozzle block. 60
3. In a turbine, the combination of a nozzle block having a plurality of nozzle openings therein, a flexible member having one end secured in position adjacent to one end of the nozzle block for covering and uncovering the nozzle openings, a rocker member having central and lateral convex faces, the other end of the flexible member being secured in position to one end of the convexly-faced member so as to register with the central convexly-faced portion thereof, chain members secured to the other end of the rocker member and cooperating with the laterally-disposed convex faces, and means cooperating with said chain members adjacent to the other end of the nozzle block for placing the chain members yieldably in tension, whereby the flexible member is main- 65
4. In a turbine, the combination of a nozzle block having a series of nozzle openings therein, a seat member secured thereto and having a plurality of perforations over each nozzle opening, and a rocker member cooperating with the seat member for successively covering and uncovering the perforations and nozzle openings. 70
5. In a turbine, the combination of a nozzle block having a series of nozzle openings therein, a seat member secured to the block and having a group of perforations over each nozzle opening, a flexible member for covering and uncovering the perforations and nozzle openings, and means cooperating with the flexible member for causing the latter to cover and uncover the nozzle openings in succession. 75
6. In a turbine, the combination of a plurality of substantially parallel nozzle blocks, each of which is provided with a plurality of nozzle openings, means for covering and uncovering the nozzle openings of each block, a lever connected to each of said means, and an actuating link connected to said lever nearer to one of the means than to the other, whereby, when said link is moved, one of said means will be operated and then the other in succession. 80
7. In a turbine, the combination of a plurality of nozzle blocks each of which has a plurality of nozzle openings therein, flexible members secured adjacent to corresponding ends of the blocks, rocker members secured, respectively, to the opposite ends of the flexible members, means cooperating with each of the rocker members to maintain the flexible members taut and in contact with the nozzle blocks, links connected to each of the rocker members for rocking the latter, a lever pivotally connected to each of said links, and an actuating link pivotally connected to said lever at a point nearer to one of said rocker connecting links than to the other, whereby, the rocker members will be actuated one at a time and in succession to successively cover and uncover the nozzle openings of each nozzle block. 85

In testimony whereof, I have hereunto subscribed my name this 2nd day of January, 1923.

HERBERT T. HERR.
